UNITED STATES PATENT OFFICE

FRANK J. RAUCHUT, OF PHILADELPHIA, PENNSYLVANIA

BROOM AND MOP HOLDER

Application filed October 4, 1932. Serial No. 636,203.

The invention relates to broom and mop holders.

The present invention is an improvement upon the broom and mop holder construction shown in my Patent No. 1,485,092, granted February 26, 1924.

The present invention relates to a broom and mop holder construction made primarily of sheet metal, and one object of the invention is to make such a construction light, strong, efficient and practical in service.

According to the invention of said Patent No. 1,485,092 and also according to the construction of the present invention, there is a central triangular or trapezoidal portion, to wit, a substantially triangular portion, providing downwardly and outwardly extending faces upon and along which gripping rollers can operate, vertically extending end members or handle resisting and holding members against which handles of brooms, mops, or the like, can press and be held by and because of the wedging effect of the gripping rollers. The construction is such that downward movement of the handles when in place causes or allows the gripping rollers to engage the handles each at one side thereof and to press the handle engaged thereby outwardly against the end member corresponding thereto.

One aspect of the present invention contemplates the forming of these gripping rollers of a yieldable resilient material such as rubber and providing on the peripheral portions of each roller what may be termed peripherally arranged grooved portions thus providing rib portions extending in the same general direction as the axis of the roller.

With these and other objects in view, the invention consists in the construction and novel combination and arrangement of parts hereinafter fully described, illustrated in the drawing and pointed out in the claims here-to appended, it being understood that various changes in form, proportion, and minor details of construction within the scope of the claims may be resorted to without departing from the spirit or sacrificing any of the advantages of the invention.

Reference will now be made to the draw-

ing forming a part of this specification, and in which drawing

Figure 1 is a general assembly front elevation view of the broom and mop holder;

Fig. 2 is a vertical view or end elevation of the same;

Fig. 3 is a front vertical view of a sheet metal front member of the holder;

Fig. 4 is a front view of a sheet metal plate from which the back or body member of the holder is made;

Fig. 5 is a front view or vertical elevation view of the back or body member;

Fig. 6 is a horizontal sectional view taken as on the plane indicated by the lines 6—6 of Fig. 5 looking in the direction of the arrows;

Fig. 7 is a plan view of the back or body member shown in Fig. 5; and

Fig. 8 shows in perspective a rubber clamping roller such as is used in the arrangement of Figure 1.

Reference will now be made to the drawing in detail.

From Figs. 1 and 2, it will be observed that the broom and mop holder comprises, besides the two indicated clamping rollers, a back or main body member of sheet metal and a front member of sheet metal secured as by rivets to the body member.

Therein the broom and mop holder as a whole is designated by 1. It comprises the sheet metal body member or back member designated as 2, and the sheet metal front member 3 that is secured to the back or body member as by means of rivets 4, 5 and 6. In fact these parts are shaped so as to provide not only the handle receiving sections 7 and 8, but also the suitable receiving spaces for the gripping rollers designated by 9, shown in position in Figure 1 and in perspective in Fig. 8, the front plate 3 is clearly shown by itself in Fig. 3. As above stated, it is of sheet metal, it is substantially rectangular in shape and is provided with openings as 10 into and through which the rivets 4, 5 and 6 pass that are relied upon for holding the front member 3 in position in respect to the body member.

The body member 2 is made from a sub-

stantially rectangular sheet of metal indicated by 11 in Fig. 4. The dotted lines A—B—C—D and E—F indicate the location of the main bends to which this sheet of metal is subjected in producing the body member shown more clearly in Figs. 5, 6 and 7. When the plate shown in Fig. 4 is bent so as to produce the body member shown in Figs. 5, 6 and 7, it will be observed that the following characteristics exist. Assuming that the parts occupied in position which the broom and mop holding occurs when in use, then it will be observed that the part A—B—B—A provides a centrally located forward portion that extends vertically and transversely, that from the lateral edges of this trapezoidal or triangular shaped forward section that rearwardly extends downwardly and outwardly inclined roller supporting surfaced portions defined by the parts A—B—D—C which are in the forms of parallelograms, that from the rear edges C—D of these parallelogram sections that extend outwardly what may be termed vertically and transversely extending substantially trapezoidal spacing sections defined by C—D—E—F, the outer edges of which, E—F, extend substantially vertically and that from the edges E—F there forwardly projects end sections or handle resisting members defined by E—F—G—H. As a matter of fact, the end sections E—F—G—H, while in effect rectangular in form, are outwardly bowed along the central portions thereof as indicated at J to provide a curved receiving space for the handles of the broom or mop.

The forward central section is provided with rivet receiving openings 12 whereby the front plates can be secured to the back member through the medium of the rivets 4, 5 and 6, as previously referred to. It will be also observed that the ends G—H indicated by 13 in Figs. 6 and 7 practically extend forwardly to the plane defined by the front of the trapezoidal central portion A—B—B—A and which portion is designated by 14 in Figs. 6 and 7.

The front member 3 has a horizontal dimension or width equal to the length of the base A—A of the forward central trapezoidal or triangular section A—B—B—A. The outer vertical edges of the plate 3 are spaced from the forward edges 13 of the end members sufficiently to permit the insertion or removal of a mop or broom handle as and when desired. It will also be noted that the distances between the outer vertical edges of the front plate 3 and the edges 13 are less than the diameter of the compression roller 9 employed in the device. It will also be noted that each horizontal surface element of the parallelogram inclined sections A—B—D—C extends at right angles to the vertically and transversely ex-

tending face portion A—B—B—A, as is apparent from inspection of Fig. 6. In other words, this inclined section is positioned so that because of the horizontal surface supporting elements just mentioned the substantially cylindrical rollers 9 will properly rest against the same. Holes 15 are provided in each of the trapezoidal spacing sections C—D—E—F, whereby the device as a whole can be suitably supported in place as by nails in a wall structure and in order to facilitate the inserting of the nails through this back member these holes are located outwardly in respect to the side edges of the front member 3. It will also be observed that small hook shaped members, as 16, 17 and 18, are provided, the hook member 16 being provided in the front central portion of the structure and is held in place by means of a rivet 5 so that the hook portion can extend forwardly and upwardly in respect to the front plate 3. The side hooks 17 and 18 are riveted to the central portion of the vertically extending end sections so that the hooks extend outwardly and upwardly in respect thereto but in such a manner that the rivet heads 19 at the inner side of said end sections do not substantially extend beyond the inner faces of said end sections.

What I claim:

1. A broom and mop holder comprising a sheet metal body member, a sheet metal front member connected to the body member and two clamping rollers in association with said members, said body member being formed of a sheet of substantially rectangular shaped metal bent so as to provide a vertically and transversely extending central forward section of substantially triangular configuration with the base of the triangle arranged lowermost, from the inclined side edge portions of said central forward section there rearwardly extends downwardly and outwardly inclined parallelogram shaped sections, having horizontal surfaced elements that extend at right angles to the central forward section, from the rear portions of which parallelogram shaped sections there outwardly extend vertically and transversely extending bridging sections each substantially trapezoidal in configuration and having a vertically extending outer edge, and extending forwardly from each of the outer edge portions of said trapezoidal bridging sections a vertically extending end section or handle resisting member, the sheet metal front member being arranged so that it extends vertically and transversely and being substantially rectangular in shape and of a width substantially equal to the length of the base portion of the forward central substantially triangular body section whereby there is provided a receiving and holding space for the clamping rollers, the outer

- edges of the central rectangular section and the forward edges of the end sections or resisting members being spaced a sufficient distance from each other to permit the insertion therethrough of a mop or broom handle but being of less distance than the diameter of the clamping rollers, one of which clamping rollers is positioned between one of its end sections and its corresponding inclined parallelogram shaped sections and the other of which rollers is provided between the other end sections and its corresponding inclined parallelogram shaped section.
- 15 2. A broom and mop holder as defined in and by the claim last preceding, in which the rollers are of rubber and have peripherally arranged corrugations providing rib portions paralleling roller axes.
- 20 3. A broom and mop holder constructed as defined in and by claim 1, in which the body member is provided with spaced openings for receiving securing means which openings are arranged in the bridging sections and are located outwardly in respect to the edges of the sheet metal front member and in which there is provided three auxiliary hooks one of which is secured in front of the central portion of the sheet
- 25 metal front member and extends upwardly and forwardly therefrom and the other two of which hooks are secured to the end sections or resisting members and extend outwardly and upwardly therefrom.
- 30 35 In testimony whereof I hereunto set my hand.

FRANK J. RAUCHUT.
